UNITED STATES PATENT OFFICE.

IRVING W. STEVENS, OF HENRY, ILLINOIS.

MAGAZINE-PIPE.

No. 906,328.

Specification of Letters Patent.

Patented Dec. 8, 1908.

Application filed January 6, 1908. Serial No. 409,400.

To all whom it may concern:

Be it known that I, IRVING W. STEVENS, citizen of the United States, residing at Henry, in the county of Marshall and State 5 of Illinois, have invented certain new and useful Improvements in Magazine-Pipes; and I do hereby declare that the following is a full, clear, and exact description of the invention, which will enable others skilled 10 in the art to which it appertains to make and use the same.

This invention relates to improvements in tobacco pipes.

The object of the invention is to provide 15 a pipe with a receptacle or magazine for tobacco.

A further object is to provide a receptacle for tobacco and combine therewith means for discharging the tobacco into the bowl of the 20 pipe.

To the end that my invention may be understood I have provided the accompanying drawing in which

Figure 1 is a vertical longitudinal section 25 of the pipe. Fig. 2 is a top view of the same. Fig. 3 is a transverse section on line X X, Fig. 2. Fig. 4 is a transverse section of part of the pipe showing a lid or cover raised over its hinge.

30 A indicates the bowl of the pipe. Connected with its interior is a passage B, formed in an extension C of the pipe, which communicates with a vertical passage D in said extension C. This extension is provided 35 with a containing space E in which tobacco is to be stored, its top being flush with the top of the pipe bowl. It is closed by means of a lid, or cover, F which, as shown in Figs. 3 and 4, is hinged to the side as at G and 40 preferably has a lip H which overlaps the sides and one end of the magazine and is provided with means for holding it shut, as for instance, by means of a notch J in the side of the extension C and a projection K 45 on one of the lips to enter said notch; the spring of the lip, or flange, holding said projection in the notch. The end of the lid at the bowl A is cut out as at L to leave the 50 opening of the bowl free but which is designed to rest snugly upon the top of said bowl so as to make the receptacle or magazine practically air tight. The rear end of the cover is notched at M to provide for the stem N which has a vertical threaded portion

55 O extending into a threaded socket P in the wall of the extension C as shown in Fig. 1;

the passage in the stem communicating with the vertical passage, already described, and thence with the pipe bowl through the passage B.

60

In the wall of the bowl A and communicating with the receptacle or magazine E is an aperture Q opposite which, and inside the said magazine, is a plunger R supported from the lid F. Said lid has a slot indicated 65 by S which is covered by a slide T. This slide carries a finger piece or button U, and depending from said slide through the slot are two members V attached to and carrying the plunger R and by which the latter is 70 suspended in a horizontal position and also by which it can be shifted in the direction of its length.

75

Located in the magazine E to move vertically therein is a horizontal plate W beneath which is a spring 2 constantly tending to raise the plate. The magazine is filled by opening the lid F and pouring the tobacco upon the plate W which is held down by the finger until it is full of tobacco. 80 When the magazine is full the lid is closed and held down against the pressure of the spring by means of the catch K or any other suitable form of lock that may be provided. The slot S is always covered by 85 the slide T and the cover F fits the magazine as snugly as is practicable so that the moisture in the tobacco cannot escape. The normal position of the plunger is within and filling the aperture Q so that moisture cannot pass through said aperture. When it is desired to fill the pipe bowl the plunger is drawn backward in the direction of the stem N by means of the knob U which allows the tobacco to get between its end and the aperture Q. Then by pushing the plunger toward the aperture the tobacco is pushed through it into the bowl. A number of strokes of the plunger backward and forward will result in filling the bowl with 90 tobacco to the desired height.

95

As the tobacco is removed from the magazine the spring 2, constantly tending to raise the plate W, as already stated, will keep tobacco always raised in the vicinity of the 100 plunger and against the lid F so the plunger can eject it. Evidently means may be employed for positively holding the plunger in its normal position within the aperture Q if desired.

105

110 By extending the passages B and D around the magazine in the manner shown a "long

stem" and consequently a large cooling area is provided. Near the juncture of the passages their ends extend through the wall of the portion C and each passage is closed 5 by plugs or screws 3 and 4, the removal of which permits said passage to be readily cleaned by the insertion of a suitable cleaning device for keeping them free of moisture and nicotin.

10 The magazine is preferably constructed of light wood while the bowl is constructed of a harder sort, such as the usual "brier" or similar wood, or said magazine may be made of aluminum which can be attached 15 to the brier wood bowl, the purpose in any event being to make the pipe so as to weigh no more than those now in use.

In constructing a pipe with a magazine it is the intention that the pipe may be 20 as convenient as possible in that it may be filled several times from said magazine without necessitating the use of a tobacco pouch or other receptacle usually carried separate from the pipe. It is evident that other constructions may be readily contrived as it is 25 not my purpose to be confined necessarily to what is shown and described, and in fact the plunger may be eliminated and the aperture Q made sufficiently large in order that 30 the pipe may be tilted so that the tobacco may fall from the magazine into the bowl assisted by shaking or by tapping or jar- ring the pipe.

Having described my invention, I claim:

35 1. The combination with the bowl of a tobacco pipe, of a tobacco storage receptacle adjacent thereto, said receptacle having means of communication near its top with the said bowl.

40 2. In a tobacco pipe the combination of a bowl having an aperture near the top thereof, a tobacco storage receptacle adjacent to said bowl and with the top of which the aperture communicates, and a closure for the 45 said receptacle.

3. In a tobacco pipe, the combination of a bowl having an aperture near the top thereof, a tobacco storage receptacle adjacent to said bowl to communicate with the latter 50 through its said aperture, means tending to raise the contents of the receptacle toward the aperture, and a closure for said receptacle.

4. In a pipe, a receptacle for the storage of 55 tobacco, a lid for the receptacle, and means of communication between the receptacle and the bowl of the pipe, and means for raising the tobacco to the place of such communication.

60 5. A pipe having a receptacle for the storage of tobacco, means of communication between the receptacle and the top of the bowl of the pipe for the passage of tobacco from

the former to the latter, a lid for the receptacle, and means for raising the tobacco and 65 holding it against the lid and in the vicinity of the place of communication.

6. A pipe having a receptacle for the storage of tobacco, there being an aperture through the bowl of the pipe connecting the 70 latter with the receptacle, and means in the bottom of the receptacle constantly tending to hold the tobacco in the vicinity of the place of communication.

7. A pipe having a receptacle for the storage of tobacco, a lid for the receptacle, there being an aperture through the bowl of the pipe connecting the latter with the receptacle, and means in the bottom of the receptacle constantly tending to hold the tobacco 80 in the vicinity of the means of communication.

8. A pipe having a receptacle for the storage of tobacco, a closure for the receptacle for retaining the moisture in the tobacco and 85 retaining the tobacco in said receptacle, means of communication between the receptacle and the bowl of the pipe, means constantly tending to force the tobacco into the vicinity of the place of communication, and 90 a device within the receptacle for positively carrying the tobacco from the receptacle into the bowl of the pipe.

9. The bowl and stem of a pipe, there being a passage connected with the bowl, there 95 also being a passage connected with the stem, said passages extending substantially at right angles to one another, each said passage opening through the wall of the pipe, and means for closing said passages for the 100 purposes set forth.

10. In a tobacco pipe, the combination with its bowl, of a tobacco receptacle adjacent thereto and communicating near its top with the bowl, there being an aperture for 105 such communication, a mouth piece for the pipe, there being a passage by which the said mouth piece communicates with the bowl, the said receptacle having a position between the passage and the bowl, said passage extending downward beneath said receptacle substantially as shown.

11. In a tobacco pipe, its bowl, a mouth piece communicating with said bowl, there being a passage for such communication, a 115 tobacco receptacle interposed between the passage and the bowl substantially in the manner shown, and means at substantially the middle of the length of the passage by which to admit of access to the said passage. 120

In testimony whereof I affix my signature, in presence of two witnesses.

IRVING W. STEVENS.
